REPEATEDLY IGNITABLE ROD

Leopold Rado, London, England

Application August 5, 1947, Serial No. 766,331
In Great Britain May 19, 1941

4 Claims. (Cl. 44—42)

1

The present invention relates to an ignitable member, which, unlike an ordinary match, can be repeatedly ignited, and which is hereinafter called an "ignitable rod."

A rod repeatedly ignitable by friction has often been proposed, the rod being provided axially with an igniting mass. After ignition has been produced by rubbing the igniter, the organic substances begin to burn, but after the flame has been extinguished, the igniter will be found to lie deeper in the organic mass, i. e., below the end thereof, or at least flush with the end. Thus, if it is desired to make repeated use of the rod friction of the organic mass only can be brought about because, owing to its position in said mass, the igniter cannot be subjected to sufficient friction to cause its ignition.

The present invention eliminates this disadvantage by providing a repeatedly-ignitable rod made of any suitable inflammable materials, for instance a base of cellulose, nitro-cellulose, metaldehyde, or the like, and an easily ignitable substance, for example of phosphorus base with the known oxidising and combustion and retarding substances, as a core-like igniter in the rod, the igniter being movable in a forward direction, like the lead in a propelling pencil, in order that on repeated use the igniter can be moved through the rod so that its end projects out of the rod to permit of its being rubbed against a rough surface to produce the ignition of the igniter and of the rod.

For the reason that the igniter burns more rapidly than the outer part of the rod, it will be necessary in due course to refill the rod with a new igniter, and when the rod itself is burnt away it must be replaced in its holder by a new rod.

In order to move the igniter forward out of the rod, use can be made of one or the other well known propelling pencil constructions in which, by mechanical means, the igniter like the lead of such a pencil, will be pushed forward out of the ignitable rod.

The accompanying drawing shows one constructional form of the invention.

On the drawing:

Figure 1 is a sectional view of the ignitable rod with its holder and with a cap provided for the protection of the rod.

Figure 2 shows the ignitable rod with its holder and also shows the protective cap removed from the holder.

Referring to the drawing:

The combustible rod 1 which is made of organic substances, is formed with an axial bore

adapted to receive the easily inflammable igniter 2. The repeatedly-ignitable rod 1 is fixed in the part 3 of a holder or turntable, for example by screwing, the holder also comprising a handle 4 which, by means of a screw construction, on being turned moves forward a wire-like device 5, which pushes the igniter 2 the required distance forward out of the rod 1. This construction may be considered as being a turntable. The device 10 comprises a covering cap 6 to which a striking plate 7 is attached.

In order to avoid friction when the igniter 2 is moved in the rod and also the better to isolate the ignitable mass, it will be of advantage to cover the igniter by a lacquer which hardens, for example, a lacquer of a resin or cellulose mixture.

To insure that the ignitable rod 1 does not break on rough handling it can be provided with a movable case (not shown in the drawing) and 20 which always leaves free only the end of the rod required for use.

As a burnt-out rod and igniters can be replaced in the holder by fresh rods and igniters, it would be of advantage to provide a place to store 25 these reserve parts. This can be arranged by the provision of a space in the holder in the same way that reserve leads are held in propelling pencils.

In order to produce the tube-like inflammable rod 1 of organic substances, the following method 30 may be adopted. The organic substances are produced in sheet form and then rolled upon a mandrel in as many layers as required, the layers being stuck together during the rolling operation. After removal from the mandrel the tube 35 is ready and, on hardening, will be found to have great resistance.

The sheets of organic substances can be produced by the use of fibrous material such as cellulose fibre mixed with fibrous-free organic substances such as dissolved nitro-cellulose.

Fibrous materials can also be used if, previous to the rolling operation they are impregnated with hydrocarbon substances such as paraffin, 40 resin solution, nitro-cellulose solutions, or mixtures of these substances.

The adhesive such as resin for example used for sticking the layers of organic substances during rolling must naturally also be of inflammable nature, and heat and pressure can also be used 50 in the production of the said tubes to facilitate drying.

The mandrel on which the tubes will be produced must have the same diameter as the igniter part of the rod.

If resin is also present this will serve also as an adhesive to stick together the layers of sheet material on producing the tube under action of heat and pressure.

The production of repeatedly ignitable rods provided axially with a wick-like igniter was previously known and is described for example, in British Patents Nos. 401,905 and 409,291.

In the British Patent No. 401,905 is described the production of such ignitable rods, wherein, amongst other propositions, the combustible mass while in a plastic condition, is formed into the shape of tubes, and after insertion of the igniter in the tube, the tube is pressed directly around it.

In the British Patent No. 409,291 is described the manufacture of a rod consisting of a combustible mantle with a tubular hole of a diameter sufficient to allow the core to slide in the combustible mantle.

While I have disclosed herein the best form of the invention known to me at the present time, I desire it to be understood that I reserve the right to make changes and modifications in the herein described embodiment of the invention provided such changes fall within the scope of the following claims.

What is claimed is:

1. A tubular repeatedly ignitable member or rod consisting of inflammable material having a threaded outer wall at the lower end thereof, said material being nitrocellulose and provided internally with a corelike igniter, said corelike igniter being mounted for reciprocating movement within the member, and being made of an easily ignitable phosphorus base adapted on being rubbed against a rough surface to ignite and thereby cause the ignition of the adjacent end of the surrounding inflammable material, turntable means threadedly engaged with said member or rod, a wirelike device one end of which is adapted to ride within said member or rod for engaging corelike igniter and the other end of which is carried by said turntable whereby upon rotating said turntable the corelike igniter is urged forwardly out of the rod so that its end can be projected and held in a forward position out of the adjacent end of the rod when engaged.

2. A tubular repeatedly ignitable member or rod consisting of inflammable material of organic substances having a threaded outer wall at the

lower end thereof, said material being nitrocellulose and provided internally with a core-like igniter made of an easily ignitable phosphorus base mounted for reciprocating movement therein, and adapted on being rubbed against a rough surface to ignite and thereby cause the ignition of the adjacent end of the surrounding inflammable material, a turntable annularly threaded and engageable with the threads of said tube, and a wire-like device one end of which is connected to said turntable and the other end of which is positioned to abut the lower end of the core-like igniter forwardly out of said tube so that its end can be projected and held in a forward position out of the adjacent end of the rod when desired, said nitrocellulose of said rod being in sheet form.

3. A repeatedly ignitable member or rod as claimed in claim 2 characterized by the fact that the sheets of nitrocellulose are produced by the use of fibrous cellulose mixed with fibrous-free dissolved nitrocellulose.

4. A repeatedly ignitable member or rod consisting of inflammable material of organic substances having a threaded outer wall in the lower end thereof, said substances being nitrocellulose, a core-like igniter receivable within said member or rod being mounted for reciprocating movement therein, turntable means threadedly engaged with said member or rod at the lower end thereof, a wirelike device one end of which is adapted to ride within said member or rod and engage said corelike igniter and the other end of which is connected to said turntable whereby upon rotation of said turntable corelike igniter is positioned forwardly out of said rod so that its end can be projected and held in a forward position outwardly adjacent end of said rod when desired, said rod being of organic substance in sheet form.
